C. L. NEIBERG, OF NEW HAVEN, CONNECTICUT, ASSIGNOR TO SARGENT AND COMPANY, OF THE SAME PLACE.

Design No. 2,648, dated May 7, 1867.

DESIGN FOR A COFFIN-HANDLE.

The Schedule referred to in these Letters Patent and making part of the same.

TO ALL WHOM IT MAY CONCERN:

Be it known that I, C. L. NEIBERG, of New Haven, in the county of New Haven, and State of Connecticut, have invented a new Design for Coffin-Handles; and I do hereby declare the following, when taken in connection with the accompanying drawing and the letters of reference marked thereon, to be a full, clear, and exact description of the same, and which said drawing constitutes part of this specification, and represents a front view.

This invention relates to a new design for what are termed coffin-handles, and consists in the peculiar configuration of the socket, which is formed to represent a sprig or branch with several leaves thereon, and an opening bud extending downward, the base A of the bud forming the socket to which the handle is secured, and in keeping with the natural appearance of the leaves and buds, to form recesses for the several screws a by which the socket is secured.

What I claim as my invention, is—

The design for coffin-handles herein described and illustrated.

C. L. NEIBERG.
